SEATING AND CONTROLLING ATTACHMENTS FOR BARBER CHAIRS

Pinckney C. Hicks, Los Angeles, Calif.

Application August 25, 1954, Serial No. 452,105

2 Claims. (Cl. 155—81)

This invention relates to improvements in barber chairs, the same including, among other features, seating and controlling facilities for a barber. Among the objects of the invention are the provision of a comfortable barber seat with a backrest and of a controlling rack for the feet of a barber who is seated on said seat. These features are capable of being corporatively connected to conventional barber chairs and places but little weight on the chair.

By the use of my invention, a barber is materially aided in assuming the most convenient and advantageous operating positions as may be necessary for him to ply his trade most effectively upon the occupant of a barber chair. My improvements solve and overcome many objectionable tendencies of presently available attachments by providing new and improved facilities for the barber by which the seat on which the barber is seated or the chair in which his customer is seated may be rotated easily, and quietly by the barber's feet on the controlling rack to place him or the customer in any desired relative position. This mode of operation frees the hands of the barber for cutting and trimming of the customer's hair and for other barbershop manipulations. Accordingly, the barber sits comfortably with a back support the same height and distance from the customer as if standing, providing the barber seat, back rest and controlling rack are set accordingly.

In the accompanying drawings forming part of this specification,

Fig. 1 is a perspective assembly view showing my improved seating and controlling attachments as applied to a conventional barber chair.

Fig. 2 is an exploded perspective view showing portions of a barber chair pertinent to the present improvements together with portions of the present attachments.

Fig. 3 is a perspective view of a radial frame constituting part of the present improvements, showing the manner of its connection to the means shown in Fig. 2.

Fig. 4 is an underside perspective view of a barber seat carried by the radial frame of Fig. 3.

Fig. 5 is a perspective view of a controlling rack and the manner of its connection to the seat frame of a barber chair.

Fig. 6 is a detail perspective view of a connecting bracket (shown in Fig. 5) and operatively related parts.

Fig. 7 is a plan view of the controlling rack and including parts of the pedestal of the barber chair.

Referring in greater detail to the drawings, B indicates a barber seat, C a radial frame, D a controlling rack, and A a barber chair of usual construction, the latter having a pedestal 8 in which a cylinder 9 is secured. A vertical hydraulic stem 10 is operatively engaged in the socket 11 of said cylinder 9 and, in any conventional manner, said stem 10 revolves or is raised, lowered, locked or released by an operating handle 12 or the like. A seat frame 13 is connected to the stem 10 which is hydraulically operated. Connecting brackets 14 are secured to the seat frame 13 as by bolt and nut

2

assembly 15. The brackets 14 secure and permit downwardly directed arms 16, that hold the lower footrest 17, to operate. The latter is provided with arms 18 to which an upper footrest 19 is secured.

5 In Fig. 2, the vertical hydraulic stem 10 is raised out of the socket 11 which is normally within the cylinder 9, and a roller bearing 20 and cup 21 are placed around said stem 10 and on top of the cylinder 9. Said stem 10 extends through said roller bearing 20 and cup 21 and into socket 11. A split clamping collar 22 having ears 23 and holes 24, encircles the cup 21 and a pair of downwardly directed hanger arms 25 having upper holes 26, are secured in diametrically opposite positions, to said cup 21 as by a bolt and nut assembly 27. Said hanger arms 25 have a plurality of holes 28 along their lower ends. The cup 21 acts as a concentric guide, relative to roller bearing 20, for the radial frame C and the barber seat B, as best shown in Fig. 1. The vertical hydraulic stem 10 raises, lowers, revolves and/or 20 is locked in the usual manner, as explained in the patent to L. A. Carter, No. 1,770,197, dated July 8, 1930, through the roller bearing 20 and the cup 21.

In Fig. 3 is shown a pair of parallel threaded connecting end members 29 which are passed through 25 selected holes 28 at the height desired and, when the barber seat B is adjusted to the proper distance inward or outward to the barber chair A, said members 29 are secured by nuts 30. The outwardly directed ends of said parallel and threaded connecting end members 29 extend from a tubular part 31, the same continuing to form parallel arm supports 32. Each tubular part 31 has a downwardly offset portion 33 which then extend outwardly parallel toward radially offset portions 34. Axles 35 are mounted to the portions 34, the same being 35 provided with rubber-tired, ball-bearing wheels 36 that track on the floor. A vertical supporting tube 39 is offset inwardly from the axles 35 and is secured in a central position between radially offset portions 34 of arms 32, by mounting rods 37 and braces 38. Inward parts of the braces 38 are tied together by a rod 40. This forms the radial frame C that is detailed in said Fig. 3.

In Fig. 4, the seat-supporting staff 41 is normally engaged in the supporting tube 39 and may be secured at a suitable height by a clamp collar 42 placed around 45 said staff 41. A metal plate 43 is secured inward off center to the upper end of the supporting staff 41. Angular braces 44 extend from the staff 41 to the base plate 49, the same diverging from the staff 41 to the 50 base plate 49 and terminating in outbent seat-engaging ends. Barber seat B has a contour that is formed of a combination series of arcs 45, 46 and 47 together with a major rearward arc 48. The form of the seat B is such as to permit the barber to position himself between the seat B and the barber chair A with a minimum of effort. A base plate 49 forms the bottom of the seat B, the same being provided with a plurality of bolts 50 and a bolt 51 extending downwardly therefrom. Metal plate 43 and braces 44 are formed with a plurality of holes 53 through which said bolts 50 and 51 extend, 55 nuts 54 on said bolts 50 secure the assembly. This structure secures the barber seat B which is properly padded and covered, inwardly off center from the top of supporting staff 41. This inward offset permits the 60 barber seat B to be swung outwardly away from the barber chair A so that the barber may be seated, or turn and reach for tools. Metal plate 43 is provided with an outward, downwardly bent part 55, the same having two holes 56 in which parallel ends 57 of a spring-loop backrest support 58 are passed. A clamp and wing nut assembly 59 secures the ends 57 to the bolt 51 in suitably 65 adjusted relation, inward or outward with respect to

the seat B. Outwardly from 56, the ends 57 form bends 60 from which the spring-loop support 58 extends vertically. At an upper portion of said support 58 there are provided bends 61 that are inwardly offset, vertical portions 62 extending from the latter bends 61. This arrangement permits suitable inward adjustment of the backrest 63 that is connected to the portions 62 which provides vertical adjustment for said backrest 63 as by a bolt, clamp and wing nut assembly 64. A loop connects the ends of the parts 62. Desired adjustments for backrest 63 to the seat B is afforded by the above-described means.

In Fig. 5, the controlling rack D has an inner arcuate supporting member 65 and an outer arcuate supporting member 66, in spaced parallelism, and a plurality of connecting radial grate bars 67. The inward ends of said grate bars 67 are secured, in coplanar arrangement, to the inner supporting member 65. The outer ends of said bars are secured on top and partly around the outer supporting member 66. Thus, a rigid support surface is provided for the barber's feet. The spaces 68 formed between the grate bars 67 permit hair cuttings to fall through onto the floor and, thus, keeps the rack D clear of hair. The controlling rack D is supported by horizontal portions 69 of hanger or suspending rods 70 which have upper threaded connecting ends 71.

In Fig. 6, a plurality of adjustable brackets 72, having upper horizontal portions extending outwardly and provided with holes 75, are adjustably secured to the seat frame 13 by a bolt and nut assembly 15. The lower horizontal portions of said brackets 72 are formed to have slots 73, the same extending inwardly to receive the threaded connecting ends 71 which are adjustably secured by nuts 74 at suitable vertical positions. This adjustment permits the barber to raise or lower the controlling rack D to a desired height. Thus, the elevated position of the barber's feet can be set as desired for his comfort and so proper circulation in his feet and legs may be had. A too low or too high adjustment of the controlling rack D may so impair circulation in the feet and legs as to induce great discomfort.

As shown in Fig. 7, the controlling rack D is concentrically arranged around the pedestal 8 of barber chair A, the location of brackets 72 affording suitable adjusting in the mounting of the rack D on a conventional barber chair.

Fig. 1 shows how said controlling rack D and its concentric position permits the hanger arms 25 to be accommodated and move in the space between pedestal 8 and the inner supporting member 65 of said rack D. The parallel threaded connecting ends 29 rotate below the controlling rack D. Both the chair A and the seat B are under full control of the barber while on said seat B. He may rotate the barber chair A when the latter is unlocked, or he may lock the barber chair A and move the barber seat B, on the wheels 36, around the barber chair A.

The wheels 36 and the spring-loop backrest 58 are approximately the same distance outward from the barber

chair A. Also, they extend outwardly about the same distance as the upper footrest 19 of the barber chair A. Thus, the present seating and controlling attachments for barber chairs need no more space to operate in than does the chair A itself.

The barber seat B and the radial frame C move in an arc 77 of approximately three hundred and thirty-five degrees. Barber chair A moves the same distance through the same angle, stopping where inward parts 78 of braces 33 contact the striking part 79 of upwardly directed footrest arms 18 of chair A. Thus, both barber seat B and radial frame C may be placed in a position to be completely out of the barber's way on either side of the barber chair A, when the barber wishes to stand.

My seating and controlling attachments for barber chairs are secured mostly by welding, after which the parts may be plated for good appearance. May it be understood, however, that I would not like to be limited to this mode of manufacture or to particular materials above mentioned, since different methods may be employed without departing from the spirit and scope of the invention as defined in the appended claims.

Having thus described my invention, what I claim as new and desire to obtain by Letters Patent, is:

1. An attachment for a chair having a stem rotationally engaged in a pedestal and provided with a release lock which, when released, frees the chair for rotation around the axis of the pedestal, said attachment comprising an anti-friction bearing around said stem above said pedestal; a radial bracket connected to said bearing and rotationally movable about the axis of the pedestal independently of the rotational movement of the chair; a wheel-supported seat on the outer end of said radial bracket and adapted to track around the chair upon rotational movement of the bracket; and a foot-engageable support connected to and rotationally movable with the chair and adapted to be engaged by the feet of a person on said seat to effect rotational movement of the seat and the person thereon around the chair while the chair is held stationary by the lock and, upon release of the chair lock, said foot-engageable support being adapted to be moved by the feet of a person on the seat to rotationally move the chair and its occupant relative to the seat and to the person thereon.

2. An attachment according to claim 1 in which the radial bracket is disposed beneath the foot-engageable support, and a vertically adjustable connection is provided between the bearing and the radial bracket, said connection being disposed between the pedestal and the foot-engageable support.
